(57) **CLAIM**

The ornamental design for the toilet tank tablet dispenser, as substantially shown and described.

DESCRIPTION

FIG. 1 is a front perspective view of a toilet tank tablet dispenser showing the new design;

FIG. 2 is a front elevation view of the toilet tank tablet dispenser as shown in FIG. 1;

FIG. 3 is a back elevation view of the toilet tank tablet dispenser as shown in FIG. 1;

FIG. 4 is a right-side elevation view of the toilet tank tablet dispenser as shown in FIG. 1;

FIG. 5 is a left-side elevation view of the toilet tank tablet dispenser as shown in FIG. 1;

FIG. 6 is a top plan view of the toilet tank tablet dispenser as shown in FIG. 1;

FIG. 7 is a bottom plan view of the toilet tank tablet dispenser as shown in FIG. 1;

FIG. 8 is a cross-sectional plan view of the toilet tank table dispenser as shown in FIG. 1; and,

FIG. 9 is a front perspective view of the toilet tank tablet dispenser as shown in FIG. 1, showing the toilet tank tablet dispenser in a position of use with the toilet tank tablet dispenser disposed upon a toilet tank.

The evenly-dashed broken line(s) showing of a toilet tank tablet dispenser are included for the purpose of illustrating portions of the article and form no part of the claimed design. The dot-dash broken line(s) defines the bounds of the claimed design and form no part thereof.

1 Claim, 9 Drawing Sheets
